WHEEL COVER

George Albert Lyon, 13881 W. Chicago Blvd.,
Detroit 28, Mich.

Filed July 19, 1957, Ser. No. 672,952

13 Claims. (Cl. 301—37)

This invention relates generally to wheel structures and to methods of making same, and still more particularly to a cover and handle grip structure and method of attaching the handle grips or spoke simulating element to the cover.

In the past there has been considerable demand for cover structures having radially extending spoke simulating elements or handles. In the past most of the cover structures having this type of construction have been highly involved ordinarily requiring a multi-part cover structure which on occasion has involved the use of three or more circular cover members. It will be appreciated that this type of cover construction is highly involved involving close tolerances between the parts and in addition is considerably more expensive to manufacture.

The present cover structure is believed to be considerably more advantageous than prior cover constructions of this general type since the components of the cover may be more simply manufactured at a substantially reduced cost, and since the components of the cover may be assembled together much more readily.

Accordingly, an object of this invention is to provide a new and improved cover structure having ornamental and utilitarian handle grips or spoke simulating elements.

Still another object of this invention is to provide a novel method of attaching handle grips to a wheel cover.

Yet another object of the present invention is to provide handle grips or spoke simulating elements which elements are engaged under resilient tension with the cover and which may be readily assembled with and removed from the same.

According to the general features of the present invention there is provided in a wheel structure including rim and body parts, a cover structure including an annular dished portion with the dished portion having opposed radially inner and radially outer side wall areas, the side wall areas having circumferentially spaced sets of openings defined by edges, circumferentially spaced bridging elements having resiliently deflectable and collapsible end portions each cooperable with one of the sets of openings with the bridging elements spanning and reinforcing the dished portion telescopingly cooperable with the edges defining the openings, the resiliently collapsible end portions upon being collapsed being insertable into the openings and upon being released engaging under tension the edges defining the openings, and means on the cover structure for fastening the cover structure in detachable assembly with one of the rim and body parts, at least one of the collapsible end portions on each of the bridging elements provided with an offset shoulder area cooperable with the radially inner side wall area of the dished portion to resist radially outward displacement of the bridging element.

According to still other features of the present invention there is provided in a method of assembling spoke simulating elements with a dished vehicle wheel cover, the steps of cutting out openings at circumferentially

2

spaced openings in the opposed side walls of the dished area of the cover, reducing the cross sectional configuration of the spoke simulating elements thus enabling the elements to be passed through the openings in the opposed side walls of the dished area, telescoping the elements through the openings, and enlarging the cross sectional configuration of the elements placing the elements in assembly under spring tension with the edges defining the openings.

10 Other objects and features of the present invention will more fully become apparent in view of the following detailed description taken in connection with the accompanying sheets of drawings illustrating therein several embodiments and in which:

Figure 1 is a side elevation of the wheel structure;

Figure 2 is an enlarged fragmentary cross sectional view taken substantially on the line II—II of Figure 1 looking in the direction indicated by the arrows;

20 Figure 3 is an enlarged fragmentary rear elevation of the cover with one of the bridging elements shown in a collapsed position;

Figure 4 is an enlarged fragmentary cross sectional view similar to Figure 3 only showing the bridging element in an expanded position in self retaining cooperation with the cover;

25 Figure 5 is an enlarged cross sectional view taken substantially on the line V—V of Figure 4 looking in the direction indicated by the arrows; and

Figure 6 is an enlarged cross sectional view similar 30 to Figure 2 only illustrating a modified cover structure. As shown on the drawings:

The reference numeral 10 indicates generally the wheel structure which wheel structure has a conventional wheel comprised of a body part 11 and a multi-flanged tire rim

35 12. The tire rim 12 supports a conventional tire structure 13 which may be either of the tube or tubeless type and which is adapted to be inflated by inserting air in the valve stem 14 shown in Figure 1. The body part and tire rim are suitably joined together at 15 by means of 40 welding and the like. The body part 11 is provided with a bolt-on flange 16 which flange has a series of apertures 17. The apertures 17 are adapted to be aligned with lugs positioned on the axle of a vehicle and then guided in assembly therewith with nuts (not shown) threaded onto the lugs to clamp the body part 11 to the axle.

45 The tire rim 12 includes a generally radially outwardly extending annular rim flange 18 and a generally axially outwardly elongated terminal rim flange 19.

50 Cooperable with the above defined wheel is a novel cover structure 20 for overlying the wheel which cover structure includes a circular cover member 21 and a series of circumferentially spaced spoke-simulating elements or handle grips 22.

The circular cover member 21 includes a central crown 55 area 23 which is bounded at its outer periphery by an annular dished portion 24 defined by opposed side wall areas 25 and 26. Disposed at the outer periphery or boundary of the dished portion 24 is an annular margin 27.

60 The cover structure 20 may be provided with any suitable means for maintaining the cover structure in assembly with the vehicle wheel. Preferably, the cover is provided with some kind of snap-on, pry-off type of retaining means. In the illustrated instance the cover margin 27 is turned under and formed into an annular resiliently deflectable cover flange structure 28 for self retaining cooperation with the terminal rim flange 19.

65 The flange structure 28 includes a radial flange 29 spaced axially inwardly of the cover margin 27 which flange is connected to a generally radially and axially inwardly extending flange 30. The annular flange 30 is provided at circumferentially spaced intervals with gen-

erally wedge shaped axially inwardly extending flanges which are returned bent providing generally radially and axially outwardly extending terminals 31 which terminals have edges 32 for edgewise biting engagement with the terminal rim flange 19.

The dished cover portion 24 is provided with circumferentially spaced sets of openings 33 which openings are suitably cut out of the side wall areas 25 and 26. The openings 33 in each set are in generally radial alignment as illustrated. However the openings may be staggered if desired.

The spoke simulating elements 22 each are generally C-shaped in the illustrated form although they could be of any other suitable configuration such as U-shaped if desired. The elements 22 which also comprise a split type annular tubular ring are provided with resiliently deflectable means in the present embodiment comprising end portions 34 which are joined together at a common base 35. These end portions are resiliently deflectable and the flexible nature of the elements 22 is illustrated in Figures 3 and 4. Figure 3 shows the elements 22 while under manual tension at which time they have a reduced cross sectional configuration. Figure 4 shows the elements after they have been manually released at which time they have an expanded or enlarged cross sectional configuration.

It should be noted that the opposite ends of the elements 22 are provided with means for positively precluding radial movement of the elements with respect to the cover 21. To this end, the radially inner end of the elements 22 are provided with annular turned flanges 36 which flanges are adapted to abut against the radially inner face of the side wall area 25 to preclude radially outward movement of the element 22. The radially outer end of the elements 22, and more particularly the resilient end portions 34, are each provided with off set turned tabs 37. The tabs 37 are adapted to cooperate with the radially outer face of the side wall area 26 in much the same manner as mentioned above in connection with the opposite end of the elements 22. These tabs 37 are operable to resist radially inward displacement of the elements 22 by virtue of their engagement against the side wall area 26 (see Fig. 4).

The elements 22 are of a tapered configuration so that the radially outer end may be readily telescoped through the openings 33 in the side wall area 25 and thereafter telescoped through the opposed opening 33 in the side wall area 26. Before the element 22 may be assembled, the end portion 34 of the element 22 must be collapsed in order to allow the element 22 to pass through the opposed openings 33 in the side wall areas 25 and 26. After the element 22 has been telescoped through the opposed openings 33—33 the collapsed end portions 34 are released. Upon the release of the collapsed end portions 34, the end portions 34 engage under resilient tension with the edges defining the openings 33. The reason for this is that the elements 22 normally have a cross sectional configuration slightly in excess of the size of the openings 33. Thus, when the collapsed end portions are released spring tension is set up between the elements 22 and the edges defining the openings 33.

When the end portions 34 are collapsed the tabs 37 are allowed to pass through the opening 33 in the side wall area 26. When the end portions 34 are released the annular flange 36 engages against the radially inner side of the side wall area 25 and the tabs 37 engage against the radially outer side of the side wall area 26 so that the elements 22 are precluded from radial movement with respect to the cover member 21.

The cover may be assembled upon the wheel by aligning the valve stem opening 38 with respect to the valve stem 14. Thereafter the cover structure 20 is urged axially inwardly with the edges 32 progressively cammed over the terminal rim flange 19 into assembly with the wheel. The cover may be removed from the wheel by inserting a suitable pry-off tool underneath the cover margin and twisting the tool until the cover is ejected.

Shown in Figure 6 is a modified form of the cover structure 20. In this instance primed numerals have been used to identify identical parts.

The cover structure 20' is identical with the cover 20 with the exception that the flange 34 and the tabs 37—37 have been omitted on the elements 22'. In place of the flange 36 and the tabs 37 the elements 22' are provided with grooved portions 40 at the opposite ends of the elements 22. Thus when the elements 22 are collapsed and telescoped through the openings 33' the grooved portions 40 are brought into alignment with the edges defined by the openings 33'. When the collapsed portions 34' are allowed to expand, the grooved portions 40 are brought into registry with the edges defining the openings. The grooved portions 40 provide abutment areas which engage on opposite sides of the side wall areas 25' and 26' thereby positively fastening the elements 22' to the cover 21' to resist radial displacement.

The cover structure 20' is otherwise identical to the cover structure 20 and the assembly and removal of the cover structure 20' is the same as with the cover structure 20.

In view of the foregoing description it is believed that the method of attaching the handle or elements 22 and 22' is clear and further description is not believed to be necessary.

It will be further appreciated that the elements 22 and 22' are highly advantageous in providing means for reinforcing the dished portion 24. Still further, the spoke simulating elements 22 and 22' are highly attractive and provide handles by which the cover may be readily gripped so that alignment between the valve stem and the valve stem opening in the cover may be readily brought about, and so that the cover structure 20 and 20' may be more readily pressed into assembly with the wheel by means of holding the cover structure by the handles 22 and 22'. These handles also aid in the removal of the cover in providing a cover area which may be readily gripped and pulled axially outwardly.

It will be understood that modifications and variations may be effected without departing from the scope of the novel concepts of the present invention.

I claim:

1. In a wheel structure including rim and body parts, a cover structure including an annular dished portion with the dished portion having opposed radially inner and radially outer side wall areas, said side wall areas having circumferentially spaced sets of openings defined by edges, circumferentially spaced bridging elements having resiliently deflectable and collapsible end portions each cooperable with one of said sets of openings with said bridging elements spanning and reinforcing said dished portion telescopingly cooperable with the edges defining the openings, said resiliently collapsible end portions upon being collapsed being insertable into the openings and upon being released being engaged under tension with the edges defining the openings; and means on the cover structure for fastening the cover structure in detachable assembly with one of the rim and body parts.

2. In a wheel structure including rim and body parts, a cover structure including an annular dished portion with the dished portion having opposed radially inner and radially outer side wall areas, said side wall areas having circumferentially spaced sets of openings defined by edges, circumferentially spaced bridging elements having resiliently deflectable and collapsible end portions each cooperable with one of said sets of openings with said bridging elements spanning and reinforcing said dished portion telescopingly cooperable with the edges defining the openings, said resiliently collapsible end portions upon being collapsed being insertable into the openings and upon being released being engaged under tension with the edges defining the openings, and means on the cover structure for fastening the cover structure in

detachable assembly with one of the rim and body parts, at least one of said collapsible end portions on each of said bridging elements provided with an offset shoulder area cooperable with the radially inner side wall area of said dished portion to resist radially outward displacement of the bridging element.

3. In a wheel structure including rim and body parts, a cover structure including an annular dished portion with the dished portion having opposed radially inner and radially outer side wall areas, said side wall areas having circumferentially spaced sets of openings defined by edges, circumferentially spaced bridging elements having resiliently deflectable and collapsible end portions each cooperable with one of said sets of openings with said bridging elements spanning and reinforcing said dished portion telescopingly cooperable with the edges defining the openings, said resiliently collapsible end portions upon being collapsed being insertable into the openings and upon being released being engaged under tension with the edges defining the openings, and means on the cover structure for fastening the cover structure in detachable assembly with one of the rim and body parts, at least one of said end portions provided with a grooved area with edge areas of the edges defining the openings nestingly cooperable with the grooved areas to resist radial displacement.

4. In a wheel structure including rim and body parts, a cover structure including an annular dished portion with the dished portion having opposed radially inner and radially outer side wall areas, said side wall areas having circumferentially spaced sets of openings defined by edges, circumferentially spaced bridging elements having resiliently deflectable and collapsible end portions each cooperable with one of said sets of openings with said bridging elements spanning and reinforcing said dished portion telescopingly cooperable with the edges defining the openings, said resiliently collapsible end portions upon being collapsed being insertable into the openings and upon being released being engaged under tension with the edges defining the openings, and means on the cover structure for fastening the cover structure in detachable assembly with one of the rim and body parts, each of said end portions provided with a grooved area with edge areas of the edges defining the openings nestingly cooperable with the grooved areas to resist radial displacement.

5. In a wheel structure including rim and body parts, a cover structure including an annular dished portion with the dished portion having opposed radially inner and radially outer side wall areas, said side wall areas having circumferentially spaced sets of openings defined by edges, circumferentially spaced bridging elements having resiliently deflectable and collapsible end portions each cooperable with one of said sets of openings with said bridging elements spanning and reinforcing said dished portion telescopingly cooperable with the edges defining the openings, said resiliently collapsible end portions upon being collapsed being insertable into the openings and upon being released being engaged under tension with the edges defining the openings, and means on the cover structure for fastening the cover structure in detachable assembly with one of the rim and body parts, said bridging elements each comprising a split ring with the collapsible end portions being flexible relative to one another and having a common junction thereby comprising the split ring.

6. In a wheel structure including rim and body parts, a cover structure including a central crown bounded by an annular dished portion with the dished portion having opposed side wall areas, said cover having circumferentially spaced openings defined by edges, circumferentially spaced C-shaped gripping elements cooperable with said openings with said C-shaped gripping elements extending radially of the central crown and the dished portion and telescoped through the openings in self retaining coopera-

tion with the edges defining the openings, said C-shaped gripping elements having resilient end portions which upon being collapsed have a reduced cross section enabling the end portions to be telescoped through the openings and which end portions upon being released exerting spring tension forces against the edges defining the openings in self retained assembly therewith.

5 7. In a wheel structure, a wheel including rim and body parts, a wheel cover section having circumferentially spaced openings defined by edges, circumferentially spaced C-shaped gripping elements cooperable with said openings with said C-shaped gripping elements extending radially of the cover section and telescoped through the openings in self retaining cooperation with the edges defining the openings, said C-shaped gripping elements having resilient end portions which upon being collapsed have a reduced cross section enabling the end portions to be telescoped through the openings and which end portions upon being released exerting spring tension forces against the edges defining the openings in self retained assembly therewith, and means on the cover section for maintaining the same in retained assembly with the wheel.

8. A cover structure for self retained disposition upon the outer side of a vehicle wheel including a central crown bounded by an annular dished portion with the dished portion having opposed side wall areas, said cover having circumferentially spaced openings defined by edges in the side wall areas, circumferentially spaced C-shaped gripping elements extending radially of the crown spanning the dished area, said elements being cooperable with said openings with said C-shaped gripping elements telescoped through the openings in self retaining cooperation with the edges defining the openings, said C-shaped gripping elements having resilient end portions which upon being collapsed have a reduced cross section enabling the end portions to be telescoped through the openings and which end portions upon being released exerting spring tension forces against the edges defining the openings in self retained assembly therewith.

40 9. A cover structure for self retained disposition upon the outer side of a vehicle wheel with the cover structure having circumferentially spaced opening defined by edges, circumferentially spaced radially extending gripping elements cooperable with said openings with said gripping elements telescoped through the openings in self retaining cooperation with the edges defining the openings, said gripping elements having resilient end portions which upon being collapsed have a reduced cross section enabling the end portions to be telescoped through the openings and which end portions upon being released exerting spring tension forces against the edges defining the openings in self retained assembly therewith, means on said cover structure for maintaining the same in retained assembly with a vehicle wheel, and abutment means disposed between said gripping elements and said cover structure to resist radial displacement of the gripping elements from assembly with the edges.

45 10. A wheel cover structure for disposition on a vehicle wheel including an annular dished portion with the dished portion having opposed radially inner and radially outer side wall areas, said side wall areas having circumferentially spaced sets of openings defined by edges, circumferentially spaced bridging elements having resiliently deflectable and collapsible end portions cooperable with said sets of openings with said bridging elements spanning and reinforcing said dished portion and being telescopingly cooperable with the edges defining the openings, said resiliently collapsible end portions upon being collapsed being insertable into the openings and upon being released engaging under tension the edges defining the openings.

50 11. The cover structure of claim 10 further characterized by the collapsible end portions on the bridging elements being provided with off-set shoulder areas cooperable with the dished portion to resist radial displacement of the bridging elements.

12. The wheel structure of claim 10 further characterized by the elements each having resilient C-shaped end portions which are collapsed slightly when engaged with the edges defining the openings to sustain the elements in assembly with the dished portion.

13. A cover structure including an annular dished portion with the dished portion having opposed side wall areas, said side wall areas having circumferentially spaced sets of openings defined by edges, circumferentially spaced bridging elements cooperable with said sets of openings with said bridging elements spanning and reinforcing said dished portion and being telescoped through the openings, each of said spaced bridging elements comprising a single piece of material, and resiliently deflectable means in-

tegral with each of the bridging elements whereby the resiliently deflectable means comprises an integral part of the material which comprises said bridging elements, said resiliently deflectable means being adapted for securing the bridging elements in assembly under tension with the cover structure.
